UNITED STATES PATENT OFFICE

WARREN F. BLEECKER, OF BOULDER, COLORADO

SYSTEM FOR SHOOTING WELLS BY RADIO

Application filed September 7, 1926. Serial No. 133,994.

5 My invention relates to a system and apparatus for shooting oil wells and its primary object resides in providing in combination with an explosive, a detonator and means to effect the operation thereof through the medium of an electric current set up by electro-magnetic waves produced in a distant sending element of wireless transmission.

10 An embodiment of the invention has been illustrated in the accompanying drawings in the several views of which like parts are similarly designated and in which

15 Figure 1 represents a sectional view of a well showing the position of a torpedo in which the detonator and its operating medium are embodied, relative to an explosive charge in the bottom of the well, and a sending station of electro-magnetic waves, exteriorly of the same,

20 Figure 2, a sectional elevation of the torpedo adapted for use in the system, in which a receiving antenna is disposed outside the shell in which the detonator and its operating medium are enclosed,

25 Figure 3, a similar view illustrating the construction of a torpedo having its antenna within the shell or casing,

30 Figure 4, a diagrammatic view of the detonator circuits of the torpedoes shown in Figures 2 and 3,

35 Figure 5, a similar diagrammatic view of a circuit of modified form and arrangement,

Figure 6, an enlarged sectional and partially diagrammatic view of an antenna adapted for use in a torpedo of the type illustrated in Figure 2, and

40 Figure 7, a section taken on the line 7—7 Figure 5.

Referring first to Figure 1 of the drawings, the numeral 5 designates an oil well having a metal casing 6. A charge of high explosive is contained in the bottom portion of the well as at 7, and lowered upon the charge is a torpedo which embodies the detonator element 45 which, as stated hereinbefore, is actuated by electromagnetic waves produced in a wireless sending station located exteriorly of the well as indicated diagrammatically at 8.

The sending element as shown in Figure 1, 50 is of the spark gap type in which strong elec-

tro-magnetic impulses are produced by the passage of an electric spark across a gap 9 in an electric circuit as a result of the excitation of a transformer 10. Included in the circuit is an aerial 12 which sends out the electro-magnetic waves produced in the oscillatory circuit, for the purpose of exciting a current in a corresponding antenna of the torpedo as will hereinafter be described.

5 The sending element as described is preferred by reason of its simplicity and reliability in producing electro-magnetic waves of the required strength and frequency but it is to be understood that other arrangements may be employed, such as one in which the transmitter employs undamped waves, using an oscillating vacuum tube. The circuit of the transmitter includes as usual, a condenser 13 to give capacity to the circuit, and it may include choke coils 14 for the purpose of 60 protecting the transformer.

Now referring to Figure 2 of the drawings, the torpedo comprises a carrier preferably in the form of a metal shell 15 hermetically closed at its top by a flanged plug 16 fastened by means of screws 17. A gasket 18 of resilient material is placed between the edge of the shell and the flange of the plug, and the plug has a central opening for the passage of the wires of an electric detonating circuit 70 within the shell to an antenna outside the same.

75 The antenna 19 may be composed of a loop wound on an insulating body 20 and protected from moisture and other harmful influences by a covering 21 made of gutta-percha, paraffin or the like as shown in Figures 6 and 7.

80 The body has a screw-nipple 22 by means of which it is fastened in the opening of the plug 90 of the torpedo-shell and the nipple has bushings 23 of non-conducting material for the passage of the terminal ends of the antenna loop.

85 Inside the shell is a tubular container 24 95 in which are disposed a charge of explosive as at 25, one or more caps 26 adapted to ignite the charge by the passage of an electric current, a dry battery cell 27, and a coherer 28. The battery is the source of electricity of the 100

detonator circuit which as best shown in Figure 4, includes a conductor 29 connecting a pole of the source of electricity with a terminal of each of the caps and having a break in which the coherer is connected, and a conductor 30 which connects the opposite pole of the source with the other terminals of the caps.

The circuit by which the coherer is excited through the waves transmitted to the receiving antenna 19 from the transmitter and which may be considered as being in operation a part of the detonator circuit, comprises two conductors 31 which connect opposite ends of the antenna with opposite ends of the coherer, and a condenser 35 included in one of the conductors.

The form of the torpedo illustrated in Figure 3 differs from that hereinabove described mainly in that the antenna is enclosed within the shell. Since the antenna is thus protected from moisture and other influences it requires no covering and may be made of a loop wound upon a simple support mounted in any convenient manner in the container.

The shell 32 is made of glass or other non-conductive material, and a glass cover 33 at its upper end is held in place by tie rods 34. In case the coherer will not carry sufficient current to complete the detonator circuit to fire the initial explosive charge of the torpedo, a relay circuit including a relay switch 36 and a battery 37 may be employed to provide a current of augmented strength as indicated in the same view.

It is to be understood, however, that the relay-switch is desirable only where circumstances require the provision of an increased current flow to operate the caps which ignite the charge in the torpedo. Under ordinary conditions the relay may be omitted, since owing to the limited distance between the sending station and the mouth of the well and the receiving antenna of the torpedo near the bottom of the same, no great amount of sensitiveness is required to decrease the resistance in the coherer when struck by the electromagnetic waves, so as to transmit sufficient current to explode the detonators.

In the foregoing description the controlling element of the detonator circuit has been referred to as a coherer and the drawings have been correspondingly made to include an element of this particular type. It will be readily apparent, however, that the system is not restricted to the use of a coherer since any device having a resistance which is normally very high but greatly decreases under the influence of electro-magnetic waves, may be employed within the scope of the invention.

As an example of substitutions of the above stated character, a vacuum tube may be so connected in the circuit that the electro-magnetic waves from the transmitter cause an

increased flow of current in the plate-circuit.

Other variations in the arrangement and construction of parts both at the sending station and the receiving end of the system may be resorted to without departing from the spirit of the invention which, broadly, consists in the ignition of an explosive charge by electro-magnetic waves generated at a distant point, for the main purpose of blasting or shooting oil wells or other similar shafts sunk into the earth.

It will be evident that the system provides a means for igniting the charge in the well at any selected time without the use of connections such as are employed in the present systems of shooting wells by electricity, and that owing to the strength of the electromagnetic waves excited at the sending station, required for the proper functioning of the cooperating parts at the receiving end, the system is of necessity so insensitive as to be secure against the influence of waves of ordinary strength such as those produced in radio transmission.

In the operation of the system the torpedo is lowered into the well upon a main explosive charge previously or simultaneously placed in the bottom portion of the same. The transmitting station at the mouth of the well is energized by excitation of the transformer through the medium of a switch 38, for the production of electromagnetic waves which are radiated by the aerial 12 and received by the antenna 19 of the receiving element at the bottom of the well.

The electromagnetic waves, striking the antenna circuit of the receiving device, increase the conductivity of the coherer or other electroreceptive appliance and cause increased current to flow through the detonator circuit, which in consequence ignites the initial charge of the torpedo. The charge thus exploded fires the main charge in the well.

It will be understood that where a coherer is used as the resistant element, current may constantly pass through the detonator circuit, which current however is insufficient to ignite the caps, until the conductivity of the coherer is increased by the electromagnetic waves generated at the sending station. In case a vacuum tube is employed, the detonator-circuit receives current only when the electro-magnetic waves from the transmitter cause an increased flow of current through the plate-circuit.

The arrangement and construction of the parts collectively referred to as a torpedo in the foregoing description may also be varied within the scope of the invention. The caps may, for example, be outside the shell containing the circuits, in which case the initial charge can be omitted or the initial charge may be placed outside the shell and the caps

arranged in operative proximity to the charge.

It is further possible that the mere production of a spark in a circuit controlled by an electroreceptive device in an antenna circuit may ignite the charge and thereby avoid the use of caps.

The term "detonator" as used, embraces any element or association of elements capable of firing an explosive charge for shooting a well, and it includes a fulminate adapted to be ignited by electric or other impulse, and a priming charge adapted to be exploded by the burning of the fulminate.

If the detonator is contained in the same water tight casing as the receiving device, the priming charge must explode with sufficient violence to detonate the main explosive charge which is outside the casing, or if the detonator is outside the casing, the fulminate must be protected from moisture by suitable water-proofing means and the electrical connections between the receiving device and the detonator made by insulated wires or other electrical conductors.

The explosive, by which is understood any high explosive such as nitro-glycerin, gelatin and the like, is ordinarily placed outside the casing because of its relatively large bulk and also because the explosives at present used in shooting wells, require no protection from water, oil or other liquid.

The receiving device must obviously be protected from any liquid that may be present in the well, and in order to insure its reliable operation it should also be protected from dirt and dust or from contact with surrounding objects. For these reasons it is practical to place the receiving device in a water tight casing as herein described and shown in the drawings, and it is in accordance with good engineering practice to enclose the detonator in the same protective casing. Although as stated hereinbefore, this is not essential, it is preferred to employ the invention in this form, together with a water-proof antenna placed outside the casing.

Having thus described my invention, what I claim and desire to secure by Letters Patent is:—

1. A device for shooting wells comprising a torpedo having a casing, a detonator carried by the casing, an antenna detachably mounted on the casing and having a water proof enclosure therefor, and means in the casing to effect operation of the detonator by electro-magnetic waves transmitted to the antenna from a distant point of wave production.

2. A device for shooting wells comprising a torpedo having a casing, a detonator carried by the casing, means in the casing to effect the operation of the detonator by electro-magnetic waves transmitted from a point of wave production, a compartment

carried by the casing, and a loop antenna mounted in said compartment and in communication with the detonator.

3. A device for shooting wells comprising a torpedo having a casing, a detonator carried thereby and means in the casing to effect the operation of the detonator by electro-magnetic waves transmitted from a point of wave production, and a detachably mounted water proof compartment carried by the casing and enclosing an antenna.

In testimony whereof I have affixed my signature.

WARREN F. BLEECKER.
